UNITED STATES PATENT OFFICE.

RUDOLPH A. KOCHER, OF SAN FRANCISCO, CALIFORNIA.

SYSTEM FOR THE TREATMENT OF CELLULOSE OR THE LIKE.

1,362,875.

Specification of Letters Patent. Patented Dec. 21, 1920.

Application filed February 27, 1917. Serial No. 151,175.

To all whom it may concern:

Be it known that I, RUDOLPH A. KOCHER, citizen of the United States, and resident of San Francisco, in the county of San Francisco and State of California, have invented certain new and useful Improvements in Systems for the Treatment of Cellulose or the like, of which the following is a specification.

10 My invention relates to improvements in systems for the treatment of cellulose or the like and is particularly adapted for the treatment of cellulose with a hydrolyzing agent or agents for the purpose of changing the cellulose into other products, for example, glucose, which may then be fermented to produce alcohol. The object of the invention is to provide a system in which not only may the cellulose material be treated quickly, effectively and efficiently, but also in which the treating materials may be efficiently generated and stored and effectively recovered for continued use.

Further and more specific objects, features and advantages will more clearly appear from the detailed description given below, taken in connection with the accompanying drawing, which forms a part of this specification and illustrates more or less diagrammatically a system embodying the invention in one form.

Referring to the drawing, 1 represents a treatment container, comprising a horizontal cylinder provided with an external jacket 2, into which water may be introduced through a pipe 3 and taken off through a pipe 4 for the purpose of cooling the contents of the container 1.

If it is desired to heat the container and the contents therein, the water valves 5 and 6 are closed and steam is admitted through the pipe 7 by opening valve 8. The steam may be conducted from the jacket through a pipe 9 by opening the valve 10. If the container 1 be large, internal heating means may be provided centrally located within the container 1. I have shown for this purpose a hollow shaft 11, which hollow shaft is journaled at each end of the container and carries on one end a gear 12, meshing with a gear 13, which is driven by a belt from any suitable source of power. A steam connection may be made with the hollow shaft 11, so that steam may be introduced thereto for the purpose of heating the material in the middle of the container 1.

The shaft 11 carries four spirally arranged agitating blades or scrapers, 14 and 15, only two of which are shown, the other two being located diametrically opposite the two shown. The blade 14 tends to move the material in the container 1 in one direction horizontally of the container, while the blade 15 moves the material in the other direction, so that during treatment, these blades move the material being treated back and forth horizontally of the cylinder 1. After the treatment is completed, an outlet 16 may be opened in the bottom of the container and as the material is moved back and forth, it will be delivered to the outlet at 16 and deposited in any suitable container, which may be placed beneath the outlet.

The material is introduced into the container through a manhole 17 as from a hopper 18.

The system may be effectively used for carrying out the processes described in my applications, Ser. No. 65676, filed Dec. 8, 1915, Ser. No. 130563 filed Nov. 10, 1916 and Ser. No. 132584 filed Nov. 21, 1916, in which the treatment of wood cellulose with hydrochloric acid of at least 39% strength, under certain conditions of pressure and temperature, to hydrolyze cellulose to glucose, is described.

While the system is suitable for the use of various treating agents, it is more particularly adapted to the use of a halogen acid for the treatment of cellulose, and in particular, hydrochloric acid. The cellulose is treated with hydrochloric acid of at least 39% strength in order to bring about the desired conversion, and in order that this acid may be easily and effectively recovered, only a small amount of liquid acid is used. I preferably use only from 40 to 60% of water in the liquid acid based on the weight of the cellulose material. In order that the treating acid may be kept to the desired strength, even although the temperature is somewhat raised to hasten the conversion, I provide means for introducing the gas of halogen acid, as, for example, HCl gas into the container under pressure after the air has been withdrawn therefrom.

The hydrochloric acid gas may be stored under pressure in a tank 20 or other storage means, and leading from the tank 20 is a pipe 21, through which the hydrochloric acid gas may be introduced into the con-

tainer 1 by opening the valves 22, 23 and 24. If the gas within the tank 20 is not under sufficient head of pressure to introduce the gas into the container 1 under sufficient pressure, the valve 22 may be closed and the valve 25 opened and the force pump 26 set into operation, so that the pump 26 will force the gas into the container 1 under sufficient head of pressure. In order to determine the pressure at any time, the container 1 is provided with a recording pressure gage 27.

The treating of the material in the tank with the hydrochloric acid gas causes the temperature to be raised, and in order that the same may not be raised beyond the desired point, a recording thermometer 28 is provided for indicating the temperature within the container 1, and in case the temperature tends to rise above the desired point, cooling water or brine may be introduced through the pipe 3 into the jacket of the container to maintain the temperature at the desired value. After the conversion has taken place, the hydrochloric acid gas may be removed from the container and recovered for further use.

For this purpose, I provide in the system an air-tight container 29, containing diluted hydrochloric acid, down to the bottom of which extends a pipe 30, connected with the main pipe 21, leading to the container 1, through a valve 31. Leading from the container 29 to a water cooled condenser 32 is a pipe 33 provided with a valve 34. The condenser 31 is provided with pipes 35 connected to headers 36 and 37, pipes 35 being cooled by the surrounding cold water in the condenser, which water may be introduced through a pipe 38 and which may leave the condenser through a pipe 39.

Connected to the header 37 is a pipe 40, which leads to a scrubber or air-tight tank 41 containing pieces of pumice stone and sulfuric acid for the purpose of thoroughly drying the gas passed therethrough. The pipe 40 extends to the bottom of the scrubber 41 and is provided with a valve 42. The acid in the scrubber 41 may be renewed or removed through the pipe 43. A pipe 44 leads from the top of the scrubber 41 through a valved pipe 45 to an exhaust or evacuating pump 46. The other side of the pump 46 is connected to a pipe 47, which in turn is connected to a pipe 48 leading to the external atmosphere, the pipe 48 being provided with a valve 49. Pipe 47 is provided with a valve 50 and leads to the force or pressure pump 26. In the pipe connection between the pressure pump 26 and the main pipe 21, there is provided a pressure chamber 51 of any suitable kind, and if desired a check valve may be placed in the upper part of pipe 21 to prevent any back flow of gas from the container 1 toward the tank

20 when the gases in the container 1 are under pressure, and likewise a check valve may be placed in the pipe 30, so that when the container 1 is being evacuated, there will be no back flow of gases or vapors into the 70 container 1.

In operation, after the conversion has been carried out to the desired extent, the valve 23 being closed and the valve 24 open, the valve 31 is opened and the gas within the 75 container 1 being under pressure, immediately passes into the tank 29, where any solid foreign particles or solid matter may be taken up by the dilute hydrochloric acid, after which the gas passes through the pipe 80 33 to the condenser 32, in which practically all of the hydrochloric acid solution in the gas is condensed to form liquid hydrochloric acid solution which is collected in the header 36. From the condenser 32, the gas passes 85 in the scrubber 41, where it is thoroughly dried and purified.

From the scrubber 41, the gas passes through pipe 44 and assuming the exhaust pump valve 52 to be closed and the valve 90 53 in by-pass about the pump 46 to be open, the gas will pass directly to the pipe 47 and if it is not desired to save the same, it may be allowed to escape to the atmosphere through the pipe 48, the valve 50 being 95 closed. As it is generally desirable, however, to save this purified hydrochloric acid gas for further use, it is preferably conducted to the pressure pump 26 by closing valve 49 and opening valve 50, which pressure 100 pump will force the gas under pressure into the storing means 20, so that it may again be used for treatment of material.

After as much of the gas in the container 1 as will come off without evacuation has 105 been removed in this manner, the valve 53 is closed, the valve 52 is opened and the exhaust pump 46 put in operation to remove as much of the gaseous matter as possible from the container 1. If the temperature 110 of the container be properly adjusted, not only will all of the hydrochloric acid gas be given off from the container 1, but HCl gas will be given off from the liquid hydrochloric acid present in the material until the 115 strength of liquid acid in the material is reduced to about 20% and then if the temperature of the material be at the proper point, even a large amount of this liquid hydrochloric acid of about 20% strength, may 120 be vaporized and so withdrawn from the material in the container 1. This liquid hydrochloric acid will be condensed in the condenser 32 and so saved for further use.

When a new charge of cellulose material 125 has been introduced into the container, this hydrochloric acid condensed in the header 36 may be used to supply the necessary amount of water to the new charge in the container by opening valve 53 in the pipe 54 leading 130

from the bottom of the header 36 to the pipe 21, which leads to the container 1. Likewise, the dilute hydrochloric acid in the container 29, after it has been charged as far 5 as desirable with foreign matter, such as wood parts, etc., drawn off from the container 1 with the gas, may be discharged into the container 1 by opening valve 55.

In order that any loss of hydrochloric acid gas may be promptly and efficiently replenished to the system, I provide a gas generator at 60 of any suitable kind, from which a pipe 61 leads to the header 36 of the condenser 32, the pipe 61 being provided with a 10 valve 62. When it is desired to replenish gas to the system, the generator 60 is put in operation and as the gas is generated, valve 62 is opened and the pumps 46 and 26 set in operation, so that the gas is drawn 15 through the condenser 32 and scrubber 41 to purify the same and then is forced into the storing apparatus 20 by the force pump 26.

Before charging the hydrochloric acid gas into the container 1, it is desirable to remove 20 or exhaust most of the air from the container and this may be done by closing valve 50 and opening valve 49 and setting the exhaust pump 46 into operation. The air will then be drawn from the container 1 through 25 the pipe 21, the tank 29, condenser 32 and scrubber 41 by the exhaust pump 46 and discharged therefrom to the atmosphere through pipe 48. After the air has thus been evacuated from the chamber 1, valve 31 30 may be closed and valves 22 and 23 opened, so that gas under pressure in the tank 20 may be admitted to the container 1 as first described.

While I have illustrated only a single 40 treatment container 1, a single tank 29, a single condenser, a single scrubber, a single vacuum pump, a single force pump and a single storage tank, it is obvious that all of these elements as well as others, may be duplicated and operated in series, that is, the 45 gas obtained from the operation after the treatment of the material in the container 1 may be purified as described and then discharged into the storage means for use in a second container and so on. Likewise, the 50 hydrochloric acid recovered in the condenser 32 may be used for providing moisture and some of the acid required in a second container. Several of such systems may be 55 thus connected up in series, and, if desired, the last may be connected to the first so that a cyclic path of operation is provided. In such a case, it is not necessary that the gas recovered from one operation be put into a 60 storage means prior to its being used in a second operation, but it may be forced directly into the second treatment container by the force pump, which container thus acts as a storage means. In order that the 65 amount of evacuation of the container 1 may

be easily known, a recording vacuum gage 63 is provided on the container 1.

In using the system for the treatment of wood cellulose material, such as sawdust, to produce glucose, I preferably keep the temperature between 40 and 60° C. and the gas is preferably maintained at such a pressure as to insure a constant excess of gas above the rate of absorption of the gas by the moisture and porous material. I prefer to 70 feed the gas at such a rate as to maintain a pressure in the converter of from 40 to 60 pounds per square inch. The greater the pressure, the quicker the desired or necessary strength of acid is formed with the 75 moisture or dilute acid already present in the mixture. This strength of acid should be at least 39% if HCl is used. For convenience in actual operation, I prefer to use approximately saturated acid. The 80 strength of saturated acid is, of course, different for different degrees of pressure and temperature, so that for increases of temperature, as, for example, 40 to 60° C., the pressure must be raised at least sufficient 85 to form or maintain an acid of 39% strength. What this pressure is for any given temperature may be easily calculated. The time required to saturate large quantities of material in the manner indicated 90 varies from one-half hour to two hours, depending upon the degree of cooling, amount of agitation and pressure.

There will usually follow a short period 95 during which the material stands at a temperature of 40 to 60° C. after the necessary strength of acid has been reached and during this period of heating at this temperature, it is not always necessary to agitate the material. The higher the temperature 100 used and the greater the strength of acid used, the shorter the time it takes to produce the desired conversion. The conversion can be carried out at ordinary room temperature, although this takes somewhat 105 longer, and if desired the saturated acid may be formed at ordinary room temperatures and then later the conversion accelerated by increasing the temperature of the material. The heat formed during the absorption of the HCl gas may be used to 110 accelerate the hydrolysis. As an example, it may be stated from actual experience that material which stood in contact with acid of 42% strength had reached the maximum 115 conversion, after standing for one hour at 40 to 45° C., in one-half hour at 60° C.

Provided that the treatment is such that the cellulose is not only converted to glucose, but the glucose has to some extent been 120 reconverted to other materials, then the mass, after being dried out and removed from the container 1, may be boiled with water to reconvert these materials to glucose or to similar fermentable products. 125

The amount of water added is generally such as to form about a 30% glucose solution after this final hydrolysis has taken place. This boiling with water may take place in the container 1, the heat being applied by turning steam into the jacket 2 of the container, or by turning steam directly into the interior of the chamber or container 1. Or this step may be carried out in an 10 autoclave.

Following this step, the material may be further diluted and is ready for fermentation without the necessity of separating the glucose material from the insoluble residue 15 or lignine. The amount of acid remaining is such as to form approximately a 1% acid solution when the first water is added to form the 30% glucose solution. It is also obvious that instead of operating a number 20 of converters and connecting pieces of apparatus in series that they may be operated in parallel and if desired, the storage tanks may all be connected together. Likewise, if desired, after the conversion of 25 the material has taken place in container 1, it may be discharged into a second container of the system, wherein the hydrochloric acid may be removed therefrom in the manner described, and then it may be discharged 30 into another container 1, in which water may be added to it to produce any desired reconversion.

All parts with which the acid comes in contact are suitably protected by a coating 35 of acid resisting material.

While I have described my improvements in great detail with respect to one embodiment thereof, I do not desire to be limited to such details, since many changes and 40 modifications other than those mentioned may be made without departing from the spirit and scope of my invention in its broader aspects. Hence, it is desired to cover all systems coming within the language 45 of the appended claims.

What I claim as new and desire to secure by Letters Patent is:

1. A system for the treatment of cellulose or the like, having in combination a treatment container, means for introducing a hydrolyzing acid gas into said container and means for withdrawing said gas from said container and storing it, and means for condensing a solution of the acid gas from said 55 gas, on its way to be stored.

2. A system for the treatment of cellulose or the like, having in combination a treatment container, means for introducing a hydrolyzing acid gas into said container and 60 means for withdrawing said gas from said container and storing it, means for removing moisture or water vapor from said gas on its way to be stored, and for removing foreign particles from said gas on its way 65 to be stored, and for condensing a solution

of the acid gas from said gas, on its way to be stored.

3. A system for the treatment of cellulose or the like, comprising a treatment container, with means for agitating the material therein, means for introducing halogen acid gas into said container, means for withdrawing halogen acid gas from said container and storing it under pressure and means for condensing a solution of halogen acid from said gas, on its way to be stored. 75

4. A system for the treatment of cellulose or the like, having in combination a treatment container, means for storing a gaseous cellulose hydrolyzing agent under pressure, 80 means for conducting said gas from said storage means and introducing it into said container under pressure, an exhaust pump for withdrawing the gas from said container and a force pump for forcing gas so withdrawn, into said storing means under pressure. 85

5. A system for the treatment of cellulose or the like, having in combination a treatment container, means for generating a halogen acid gas, means for storing said gas, means for forcing the gas from said generating means into said storing means under pressure, means for conducting the gas from said storing means to said container, and 90 means for withdrawing the gas from said container and conducting it to said forcing means to be forced into said storing means under pressure. 95

6. A system for the treatment of cellulose or the like, having in combination a treatment container, means for generating a hydrolyzing acid gas, means for storing said gas, means for forcing the gas from said generating means into said storing means 100 under pressure, means for conducting the gas from said storing means to said container, and means for withdrawing the gas from said container and means for removing moisture from said gas on its way to the 110 storing means.

7. A system for the treatment of cellulose or the like, having in combination a treatment container, means for generating a halogen acid gas, means for storing said gas, 115 means for forcing the gas from said generating means into said storing means under pressure, means for conducting the gas from said storing means to said container, and means for withdrawing the gas from said 120 container and conducting it to said forcing means to be forced into said storing means under pressure, and means for removing moisture from the gas on its way from the generating means to the storing means and 125 from the gas on its way from the container to the storing means.

8. A system for the treatment of cellulose material or the like, having in combination a treatment container with means for agit- 130

ing the material therein, means for varying the temperature in said container, means for forcing hydrochloric acid gas into said container under pressure and means for evacuating said container to remove hydrochloric acid gas and hydrochloric acid gas solution from the container.

9. A system for the treatment of cellulose material or the like, having in combination a treatment container, with means for agitating the material therein, means for varying the temperature in said container, means for forcing a hydrolyzing acid gas into said container under pressure and means for evacuating said container to remove acid gas and acid gas solution from the container, and means whereby both the acid gas and acid solution may be purified and stored and again returned to said container.
10. A system for the treatment of cellulose material or the like, having in combination a treatment container with means for agitating the material therein, means for varying the temperature in said container, means for forcing halogen acid gas into said container under pressure and means for evacuating said container to remove halogen acid gas and halogen acid solution from the container, means for separating the halogen acid solution from the halogen acid gas and means for returning the halogen acid solu-

tion to the treatment of material independently of the halogen acid gas.

11. A system for the treatment of cellulose or the like comprising a treatment container, means for introducing an acid gas into the container under pressure, to act upon the cellulose material or the like in the container, means for separating acid gas from the material treated and means for condensing a solution of the acid gas so separated and mixing it with a fresh charge of cellulose or the like to be treated in said container.

12. A system for the treatment of cellulose or the like comprising a treatment container, means for introducing an acid gas into the container under pressure, to act upon the cellulose material or the like in the container, means for separating acid and acid gas from the treated material and means for condensing a solution of the acid gas so separated and mixing both the acid solution and gas with a fresh charge of cellulose or the like to be treated in said container.

Signed at Decatur, in the county of Adams and State of Indiana, this 22nd day of February A. D. 1917.
